UNITED STATES PATENT OFFICE

LE BOY MARK, OF WASHINGTON, DISTRICT OF COLUMBIA

SPEECH AMPLIFYING AND REPRODUCING SYSTEM

Application filed July 16, 1927. Serial No. 206,341.

My invention relates broadly to public address systems and more particularly to a construction of microphone and amplification circuit arrangement for use in public address systems.

One of the objects of my invention is to provide a construction of microphonic pick-up and control system for public address systems in which a high degree of sensitivity is obtained for effecting reproduction of sound at relatively large volume.

Another object of my invention is to provide a construction of microphonic pick-up apparatus which is compact in size and yet which may be arranged in circuit with an electron tube amplification system for controlling the operation of the electron tube amplification system for reproduction of sound at relatively large volume.

Still another object of my invention is to provide a construction of microphonic pick-up system in which a plurality of independent microphones may be arranged in compact manner for simultaneously controlling the input circuit of an electron tube amplification system.

A still further object of my invention is to provide a construction of microphonic pick-up apparatus for public address systems in which a plurality of independent microphones are arranged in staggered relationship for actuation by sound waves and the control of an amplification and reproducing system thereby.

My invention will be more fully understood from the specification hereinafter following by reference to the accompanying drawings in which:

Figure 1 is a front elevation of the microphonic pick-up apparatus of my invention; Fig. 2 is a cross-sectional view taken through the microphonic apparatus on line 2-2 of Fig. 1; Fig. 3 is a cross-sectional view taken through the pick-up apparatus on line 3-3 of Fig. 1; Fig. 4 is a wiring diagram showing the arrangement of the multiple control of microphone system in the microphonic pick-up apparatus of my invention; Figs. 5 and 6 show front and side views of a modified construction of microphone apparatus

embodimenting the principles of my invention; Fig. 7 is a vertical cross-sectional view through the microphone apparatus of Figs. 5 and 6; Fig. 8 is a cross-sectional view taken on line 8-8 of Fig. 7; and Figs. 9 and 10 are views of the microphone support employed in the modified form of the invention illustrated in Figs. 5-8, inclusive.

Referring to the drawings in more detail, reference character 1 designates the base of the microphonic pick-up apparatus of my invention on which there is mounted a housing consisting of a front panel 2 and a rear panel 3 with end panels 4 and 5 connected thereto. A top closure 6 is provided, and between the upper surface of the supporting base 1 and the lower surface of the top closure 6 a plurality of independent microphones are mounted in vertical planes in the arrangement illustrated. I have designated the microphones at 7, 8, 9, 10 and 11, each mounted in a vertical plane as illustrated, which planes are parallel to each other but offset one with respect to the other, the center lines of the individual microphones 8 and 10 passing between the spaces which separate the microphones 7, 9 and 11. The under surface of the top closure 6 is cut away as designated at 12 forming pockets which receive the upper part of the individual microphones. The upper portion of the base 1 is cut away to provide pockets designated at 14 to receive the lower portions of the individual microphones. The pockets 12 and 14 are vertically aligned with each other thereby enabling the microphones to be rigidly mounted in position within the cabinet housing. The microphones are arranged in staggered relationship, the apertures of each microphone facing the front of the cabinet structure with the sides of the microphones overlapping. In this way, a large number of independent microphones may be positioned within a relatively small space for controlling the amplification system. The front panel 2 is apertured as represented at 15 and over the aperture an ornamental grille 16 is placed.

The circuit arrangement for the microphonic pick-up system of my invention is illustrated in Fig. 4 wherein the independent

microphones 7, 8, 9, 10 and 11 are each connected in circuit with a common source 17 and with independent primary windings 18, 19, 20, 21 and 22 of the iron core transformer 23. Each microphone has an independent primary winding, the potential across which is independently varied by the operation of its associated microphone. The transformer 23 has a secondary winding 24, the secondary winding being connected across the input circuit of electron tube 25 and arranged to function as an audio frequency amplifier. A coupling system 26 is provided between the output circuit of the amplifying tube 25 and the input circuit of the amplifying tube 27. The output circuit of the electron tube 27 includes the loud speaker 28. A suitable choke 29 and condenser 30 may be arranged in circuit with the loud speaker 28 for improving the tone quality of the reproduced sound. The conductors from each of the independent microphones are shown leading to the local source and to the several microphone circuits through twisted cables which enable the microphone to be located at a distant point remote from the amplifying system, thereby facilitating installation of the apparatus in a public address system.

The alignment of the several microphones in staggered relationship increases the number of units which may be provided within a limited area.

The modified form of microphone apparatus constructed in accordance with my invention shown in Figs. 5-10 comprise a supporting stand 42 carrying a circular band member 31 to which is secured the front and rear closure members 32 and 33 by means of screw members 50. The side closures 32 and 33 are each provided with suitable apertures 48, which apertures may be covered by a suitable ornamental grille. The grille which shows through the central aperture 51 and the apertures 48 is merely for the purpose of ornamentation as the inside wall is substantially closed by means of a felt lining 49. It serves as a sound damping chamber extending upwardly around the inside of the circular frame 31 and along the rear of the several microphones so that sound waves incident upon the several microphones strike the rear felt wall 49 and do not pass through the rear apertures 48 and 51. I provide a frame or casting 34 resiliently supported interiorly of the casing 31 by means of spring members 46 secured to lug members 47 which extend integrally from the casing 31. The spring members 46 extend substantially at right angles to each other between screw devices 43 on casting 34 and lug members 47 on casing 31. The casting 34 is provided with screw devices 43 symmetrically positioned about the casting, so that several microphones may be positioned in spacial relation and in a position for receiving sound vibrations directed thereagainst. The cast-

ing 34 includes two pairs of symmetrically arranged casing portions, each forming sockets disposed in the same plane into which microphones can be secured. The casting 34 is also provided with a socket portion 35 in a plane offset from the four socket members for receiving an independent microphone in a plane offset from the plane of the microphones in the aforementioned sockets.

I have illustrated four microphones 36, 37, 38 and 39 disposed in one plane and an additional microphone 40 in staggered relationship with respect to the aforementioned four microphones by reason of the relation of the sockets which carry the several microphones. Screw devices 41 are provided for securing each of the microphones in position. In addition to this, strap members 44 are secured beneath the heads of the screw members 43 for maintaining the microphones in position within the sockets. The strap members 43 extend over the flanges on the microphones. In order to cushion the microphones within the casing I provide cushion members 45 adjacent each of the microphone sockets, so that in the natural course of vibration of the microphones there is no danger of sudden shocks and jars which might injure the sensitive microphone devices. Connections from the several microphones lead out from the cable 43 to the control circuits of the amplifier system. It will be observed that the staggered relationship in the modified form is similar to that in the form of the invention and described in Figs. 1 to 4 in addition to the fact that more compact assembly of the apparatus is secured.

While I have described my invention in certain of its preferred embodiments, I desire it to be understood that modifications may be made and that no limitations upon my invention are intended other than are imposed by the scope of the appended claims.

What I claim as new and desire to secure by Letters Patent of the United States is as follows:

1. Microphonic pick-up apparatus comprising a frame, a casing within said frame, a plurality of sockets disposed in said casing in planes laterally offset one from the other, said sockets being arranged to receive and enclose independent microphones, at least one of said microphones being offset from a source of sound by a distance greater than the others of said microphones and spring members grouped in pairs with the pairs of each group extending substantially at right angles to each other between diametrically opposite positions on said casing and positions on the interior of said frame.

2. Microphonic pick-up apparatus comprising a frame, a carrier, pairs of symmetrically arranged sockets in said carrier disposed in a single plane, a separate socket centrally positioned in said carrier in a plane offset

from the plane of said aforementioned sockets, independent microphones disposed in each of said sockets, one of said microphones being located at a greater distance from a source of sound than the others of said microphones and means disposed between the sides of said carrier and said frame for centering said carrier within said frame.

- 5 3. Microphonic pick-up apparatus comprising a frame, a resiliently supported carrier, disposed within said frame, sockets symmetrically arranged in one side of said carrier in the same plane, a socket centrally disposed on the other side of said carrier in a plane off set from the plane of said first mentioned sockets, said sockets being arranged to receive independent microphones, said microphones being disposed in different planes with respect to a source of sound and means
10 15 extending from the interior of said frame and resiliently engaging the sides of said carrier for damping the vibration thereof.

In testimony whereof I affix my signature.
LE ROY MARK.
